CLAIM

The ornamental design for a combined paint roller and applicator unit, as shown and described.

DESCRIPTION

FIG. 1 is a side elevational view of a combined paint roller and applicator unit showing my new design, the opposite side being a mirror image thereof; FIG. 2 is a front elevational view thereof; FIG. 3 is a rear elevational view thereof; FIG. 4 is a bottom plan view thereof; and FIG. 5 is a top plan view thereof. The broken lines shown in FIG. 1 are for illustrative purposes only and form no part of the claimed design.

FIG. 1

FIG. 2

FIG. 3

FIG. 4

FIG. 5
